(57) **CLAIM**

The ornamental design for a wind spinner as shown and described.

DESCRIPTION

FIG. 1 is a bottom perspective view of my new design;

FIG. 2 is a top perspective view;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof; and,

FIG. 9 is a partial enlarged view thereof; taken from the encircled portion 9 in FIG. 1.

The dash-dash broken lines in the drawings depict portions of the wind spinner and form no part of the claimed design. The dash-dot-dash broken lines in the drawings are included to indicate a partially enlarged view and form no part of the claimed design.
